(57) **CLAIM**

We claim the ornamental design for a folding knife, as shown and described.

DESCRIPTION

FIG. 1 is a perspective view of a folding knife, showing my new design, wherein the two blades are in a retracted position; FIG. 2 is a top plan view of FIG. 1; FIG. 3 is a bottom plan view of FIG. 1; FIG. 4 is a left side elevation view of FIG. 1; FIG. 5 is a right side elevation view of FIG. 1; FIG. 6 is a rear elevation view of FIG. 1; FIG. 7 is a front elevation view of FIG. 1; FIG. 8 is a perspective view thereof wherein the two blades are in extended positions; FIG. 9 is a top plan view of FIG. 8; and, FIG. 10 is a front elevational view of FIG. 8. The knife blade that is shown in broken lines forms no part of the claimed design.
